DEVICE FOR PREVENTING SEPARATION OF PICKER STICK FEET AND STANDS

John W. Jones, Greenville, S. C., assignor to Harriett K. Bellwood, Greenwood, S. C.

Application November 24, 1942, Serial No. 466,748

8 Claims. (Cl. 139—150)

My invention relates to looms and has particular reference to a device for preventing the improper separation of the picker stick shoe from the stand or foot.

A further object of the invention is to provide a device of the above mentioned character, which is in the nature of an attachment, and may be applied to the conventional or standard picker stick shoe and stand of a loom.

A further object of the invention is to provide a device of the above mentioned character which is adjustable so that it may be applied to different sized parts, which may occur upon looms of different models.

A further object of the invention is to provide a device of the above mentioned character serving as lock means for nut of the heel bolt, which will protect the picker arm, shuttle and the parallel tongue and will also protect the heel bolt.

Other objects and advantages of the invention will be apparent during the course of the following description.

In the accompanying drawings forming a part of this application in which like numerals are employed to designate like parts throughout the same,

Figure 1 is a side elevation of a picker stick shoe and stand, showing my attachment applied thereto,

Figure 2 is a horizontal section taken on line 2—2 of Figure 1,

Figure 3 is a transverse section taken on line 3—3 of Figure 1, and

Figure 4 is an exploded perspective view of the attachment embodying my invention.

In the drawings, wherein for the purpose of illustration is shown a preferred embodiment of my invention, the numeral 5 designates a picker stick and 6 is a shoe, having an upstanding socket 7. The shoe has the conventional longitudinally curved face 7' to engage with the upper face of an oscillating stand or foot 8, mounted upon the rocker shaft 9. The numeral 10 designates a parallel tongue arranged between the picker stick and the end wall 11 of the opening 12 of the shoe 6. The parallel tongue 10 and picker stick 5 are secured to the socket 7 by a heel bolt 13, passing through an opening in the socket 7 and an opening in the parallel tongue 10 and also through an opening in a cap 14 and through an opening in a heel strap 15. This heel strap passes about the lower end of the picker stick 5 and is connected with the usual spring actuated drum 16 carried by a bracket 17. The numeral 18 designates an adjusting screw, having screw-threaded engage-

ment within an opening formed in the socket 7 and having its inner end engaging the upper end of the parallel tongue 10. By adjusting the screw 18 the parallel tongue and picker stick may be angularly adjusted with respect to the socket 7. The adjusting screw 18 carries a lock nut 19. The stand or foot 8 carries an upstanding lug 20, formed integral therewith, and this lug operates within a longitudinal slot 21, formed in the shoe 6.

The numeral 22 designates a lug strap, surrounding the picker stick 5 and supported by a check strap 23. The lug strap is operated by the usual means to swing the picker stick inwardly while the picker stick is swung by the spring actuated drum 16.

The construction thus far shown and described is of the conventional loom structure.

In accordance with my invention, means are provided to prevent the improper separation of the shoe 6 and stand 8, during operation, and this means is in the nature of an attachment. This attachment comprises a shoe carried securing device, including a unit 23' having an upstanding side 23 provided at its top with a knuckle 24. The side 23 has an opening 25 for the passage of the heel bolt 13, while the knuckle 24 has an opening 26 for the passage of the adjusting screw 18. The side 23 is arranged behind the head of the heel bolt 13 and between this head and the socket 7, while the knuckle 24 is arranged between the lock nut 19 and the socket 7. The side 23 carries a companion side 27 preferably formed integral therewith and preferably disposed at a right angle to the same. This side 27 may have an upstanding portion 28. The side 27 has a bolt 29 rigidly secured thereto, by welding or the like. The numeral 30 designates a companion unit comprising a side 31, having a longitudinal opening 32 formed through its inner end and adapted to receive the bolt 29. The side 31 carries a side 33, formed integral therewith and arranged at a right angle thereto and the side 33 carries a head 34 having an opening 35, which is polygonal, to receive the nut 13' of the heel bolt 13. The heel bolt and nut thus serve to secure the unit 30 in place, and the head 34 also serves as a lock to prevent rotation of the nut 13' of the heel bolt. The elongated slot 32 permits the relative longitudinal adjustment between the sides 27 and 31.

The numeral 36 designates a retaining element, in the form of a metal strap, disposed upon the sides of the shoe and stand 6, and having an in-turned portion or end 37, positioned beneath the stand 8, and slightly spaced therefrom, so that it

will not interfere with the normal rocking movement of the shoe 6, but will positively engage the stand 8 and prevent the separation of the shoe from the stand, during an abnormal operation of the loom. At its upper end, the strap 36 has an elongated slot 38, to receive the bolt 29. The strap is placed upon the outer face of the side 27 and inwardly of the slide 31 and therefore is arranged between the sides 21 and 31. The bolt 29 carries a nut 39, by manipulation of which the parts 28, 36 and 31 are clamped together in the selected adjusted position. The elongated slot 38 permits of the vertical adjustment of the strap 36.

It is to be understood that the form of my invention herewith shown and described is to be taken as a preferred example of the same and that various changes in the shape, size and arrangement of parts may be resorted to without departing from the spirit of the invention or the scope of the subjoined claims.

I claim:

1. A device for use in connection with a picker stick, a picker stick shoe, a stand, and a heel bolt connecting the picker stick and shoe, said device comprising an attaching member, said attaching member being provided at one end with an opening to receive the heel bolt and at its opposite end with a polygonal opening to receive the nut of the heel bolt for holding the nut against rotation, and a strap secured to the attaching member and provided with an extension to be arranged beneath the stand.

2. A device for use in connection with a picker stick, a picker stick shoe, a stand, a heel bolt connecting the picker stick and shoe, and an adjusting screw, said device comprising an attaching member, said member comprising a unit having openings to receive the heel bolt and adjusting screw and a companion unit having a polygonal opening to receive the nut of the heel bolt, adjustable means to secure the units together, and a strap to be arranged upon the side of the shoe and stand and having a part to be arranged beneath the stand, said strap being secured to the units by the adjustable means.

3. A device for use in connection with a picker stick, a picker stick shoe, a stand, a heel bolt connecting the picker stick and shoe, and an adjusting screw, said device comprising a unit, said unit having openings to receive the heel bolt and adjusting screw, a connecting bolt secured to the

unit, a coacting unit having a polygonal opening to receive the nut of the heel bolt and provided in its end with elongated slot to receive the connecting bolt, a strap having a longitudinal slot to receive the bolt and provided with a lateral extension to be arranged beneath the stand, and a nut carried by the connecting bolt.

4. A device for use in connection with a picker stick, a picker stick shoe, a stand, and a heel bolt connecting the picker stick and shoe, said device comprising an attaching member having its opposite ends secured to the heel bolt, and a strap arranged exteriorly of the shoe and secured to the attaching member, said strap having an inwardly facing part arranged beneath the stand.

5. A device for use in connection with a picker stick shoe and stand, said device comprising a strap arranged exteriorly of the shoe and stand and upon one side of the same, said strap having an inwardly facing part arranged beneath the stand, and means to securely attach the strap to the shoe.

6. A device for use in connection with a picker stick, a picker stick shoe, a stand, and a heel bolt connecting the picker stick and shoe, said device comprising a side having an opening to receive the heel bolt, and a strap arranged exteriorly of the shoe and stand and attached to said side, said strap extending upon the sides of the shoe and stand and having an inwardly facing part arranged beneath the stand.

7. A device for use in connection with a picker stick, a picker stick shoe, a stand, a heel bolt connecting the picker stick and shoe, said device comprising a side having an opening to receive the heel bolt and a second side arranged generally at a right angle to the first side and carried thereby, said device being arranged exteriorly of the shoe, a strap arranged exteriorly of the shoe and stand and secured to the second side, said strap extending across the sides of the shoe and stand and having an inwardly facing part arranged beneath the stand.

8. In a device for use with a picker stick, picker stick shoe, and a heel bolt connecting the picker stick and shoe, as a subcombination, an attaching member provided at one end with an opening to receive the heel bolt and at its opposite end with a polygonal opening to receive the nut of the heel bolt for holding the nut against rotation.

JOHN W. JONES.
